TRACK TILT CONTROL SYSTEM FOR CRANES

Filed April 20, 1949

UNITED STATES PATENT OFFICE

2,631,736

TRACK TILT CONTROL SYSTEM FOR CRANES

Robert G. Le Tourneau, Longview, Tex., assignor to R. G. Le Tourneau, Inc., Longview, Tex., a corporation of California

Application April 20, 1949, Serial No. 88,594

2 Claims. (Cl. 212—8)

1.

This invention relates to cranes of that type having an elevator track which tilts about a pivot adjacent the rear axle, as shown in my Patents No. 2,444,835, dated July 6, 1948; and No. 2,394,314, dated February 5, 1946. The present invention relates to an improved cable control system for tilting the elevator track.

It is therefore the principal object of the present invention to provide a track tilt control system which performs all of the functions of the previous invention but in a more advantageous and economical manner.

Another object of this invention is to provide a control system between the track and tongue of a crane of this type, which is cable-operated by means of an electric winch, and in which the cable is the only connection between the track and tongue.

It is also an object of this invention to provide a track tilt control system in which the heavy power unit for its operation is placed on the crane in such a manner that its weight contributes to the balance and traction of the machine.

It is an additional object to provide a track tilt control system which includes a structural frame which positions the movable sheave housing at such a position relative to the stationary sheave housing that there is suitable leverage available at all positions of operation.

A still further object of this invention is to provide a system of this type in which the structural frame on the track and the sheave housing on the tongue contain cooperating stop means to prevent excessive movement of the track in a forward direction.

These objects I accomplish by means of such structure and relative arrangement of parts as will fully appear by a perusal of the following specifications and claims.

In the drawings similar characters of reference indicate corresponding parts in the several views.

Fig. 1 is a side view of a crane embodying my improved track tilt control system.

Fig. 2 is a plan view of the movable sheave and the stationary sheave in operational alignment, but detached from the remaining structure.

Fig. 3 is a schematic showing of one limit switch wiring arrangement.

Referring now more particularly to the characters of reference on the drawing, a crane on which this system may be utilized is shown in outline in Fig. 1 to consist basically of a longitudinal tongue 1 attached to a two wheel tractor

2 at its forward end by means of steering hitch 3; the tongue is supported at its rear end by a rear wheel and axle structure 4 to which is pivoted a tilting track 5 containing an elevating boom 6 with a depending hook block 7. The method of pivoting track 5 to the rear axle structure may be either of the methods shown in detail in my previous Patents 2,444,835 and 2,394,314. Track 5 is supported at its lower end by bearings 26 on the axle 27 for tilting adjustment of said track lengthwise of the implement. The track 5 is equipped with a pyramidal frame 8 which supports and positions movable sheave housing 9 at the desired location so that ample leverage is available for tilting track 5 about its pivot even when the boom 6 is lying on the ground.

A sheave housing 10 is positioned on tongue 1 in alignment with housing 9 and cable drum 11 of winch unit 12. Cable is reeved from drum 11 under the left side sheave wheel of multiple sheave housing 10 and from there under and over corresponding sheaves of housings 9 and 10 until the cable passes over the right side sheave wheel of housing 9 from whence it passes to and is fixed on cable anchor 25 on the side of sheave housing 10.

Winch unit 12 is an electric motor driven unit which receives its power from a generator (Fig. 3) mounted on and driven by the tractor 2. Electric cable 14 delivers the electric current to winch 12 from the switch box 15 of the tractor. This winch is controlled from an electric switch located on the dash panel 18 of the operator's cockpit of the tractor. Winch unit 12, being of substantial weight, is placed forward on tongue 1 so as to counterbalance a portion of the load placed on hook block 7 and also contribute to the traction of wheels 13 of tractor 2.

If frame 8 were not included on track 5 there would be the danger of a free fall of track 5 and boom 6 after they passed top dead center when moving in a forward direction. Frame 8 and stop blocks 16 of sheave housings 9 and 10 prevent this from happening. The weight and balance of track 5 is so arranged that a constant pull on cable 17 is necessary to bring the two stop blocks together. However, if the operator kept his control switch depressed after the blocks 16 had touched there would be a danger of damaging the winch unit or breaking the cable 17; to prevent this I have provided a limit switch 19 on sheave housing 10 to be operated by cam 20 of sheave housing 9 just prior to contact of the stop blocks 16. Electric cable 21 interposes

limit switch 19 into the electric circuit of winch 12 in such a manner that when the plunger 22 of limit switch 19 is depressed, the electric circuit for rotation of the winch in a direction to reel in cable is broken; this prevents any further movement of sheave housing 9 in a direction toward housing 10. Rotation of the winch in the other direction is not effected and the track may be tilted backward whenever desired. When cam 20 moves out of contact with plunger 22, the contact is again closed and the winch may then be rotated in either direction.

In ordinary operation the stop blocks 16 will never come in contact due to the presence of cam 20 and limit switch 19. The tapered portion 23 of the cam will depress plunger 22 and thereby shut off current to the winch. However, under some circumstances, such as the dropping of a load from block 7 or the breaking of a hoisting cable, it is possible for the track and boom to come forward independent of the operation of winch 12. In these cases the cam 20 will slide by block 16 on sheave housing 10 and the two stop blocks 16 will come into abutment. This action provides an additional safety feature and will prevent damage to the machine and danger to the operator during these emergencies.

It will be noticed in Fig. 2 that housing 10 is set on the tongue 1 at a slight angle to the longitudinal center line of the machine. This was done to permit the relatively long winch 12 to have ample support from the tongue by mounting plates 24, and still permit the center line of cable drum 11 to be in substantial alignment with sheave housing 10.

From the foregoing description it will be seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention, what I claim as new and useful and desire to secure by Letters Patent is:

1. In a crane having a tongue supported by a rear wheel structure and a track pivoted to the rear wheel structure for tilting thereabout in a longitudinal vertical plane, a track tilt control system comprising a pyramidal frame structure including upstanding arms projecting a substantial distance from said track, a support member fixed to said structure at its apex, a plurality of sheaves and a sheave housing mounted on said member and movable with the track, a stationary sheave housing and a plurality of sheaves mounted therein fixed to the tongue in substantial alignment in a vertical plane with said movable sheave housing, a cable reeved between the sheaves of said housings, means for moving the movable sheaves and the track toward the housing fixed on said tongue, said means comprising said cable and a power winch mounted on the tongue adjacent the

forward end thereof, cooperative stop means mounted on said sheave housings to prevent excessive forward movement of the track, said stop means comprising: corresponding stop blocks affixed to each sheave housing, electrical means including an electric circuit to power said power winch, and a limit switch on one of said housings and an actuating device on the other housing, the switch and the actuating device being mounted to come into engagement just prior to contact of said stop blocks to open the circuit to said power winch.

2. In a crane having a tongue supported by a rear wheel structure and a track pivoted to the rear wheel structure for tilting thereabout in a longitudinal vertical plane, a track tilt control system comprising a pyramidal frame structure including upstanding arms projecting a substantial distance from said track, a support member fixed to said structure at its apex, a plurality of sheaves and a sheave housing mounted on said member and movable with the track, a stationary sheave housing and a plurality of sheaves mounted therein fixed to the tongue in substantial alignment in a vertical plane with said movable sheave housing, a cable reeved between the sheaves of said housings, means for moving the movable sheaves and the track toward the housing fixed on said tongue, said means comprising said cable and a power winch mounted on the tongue adjacent the forward end thereof, cooperative stop means mounted on said sheave housings to prevent excessive forward movement of the track, said stop means comprising: corresponding stop blocks affixed to each sheave housing, electrical means including an electric circuit to power said power winch, a plunger operated limit switch on one of said housings, a projecting bar having a cam surface on the other of said housings, the cam surface being operative to depress the plunger just prior to contact of said stop blocks to open the circuit to said power winch, said projecting bar being attached to one surface of one stop block, said limit switch being offset from the other stop block to the extent that said stop blocks will come in contact if forward movement of the track continues after contact of the bar and the limit switch.

ROBERT G. LE TOURNEAU.
